UNITED STATES PATENT OFFICE.

HERBERT H. RUSSELL, OF NEW HAVEN, CONNECTICUT, ASSIGNOR TO THE GREIST MANUFACTURING COMPANY, A CORPORATION OF CONNECTICUT.

SEWING-MACHINE RUFFLER.

1,314,705.

Specification of Letters Patent. Patented Sept. 2, 1919.

Application filed February 8, 1919. Serial No. 275,832.

To all whom it may concern:

Be it known that I, HERBERT H. RUSSELL, a citizen of the United States, residing at New Haven, in the county of New Haven 5 and State of Connecticut, have invented or discovered certain new and useful Improvements in Sewing-Machine Rufflers, of which the following is a specification, reference being had therein to the accompanying 10 drawing.

This invention relates to that class of sewing machine rufflers in which the ruffling blade is operated from the needle bar of a sewing machine. The present invention has 15 for its object to lessen the cost of manufacture by providing novel means, which may be produced at little expense, for regulating the stroke of the ruffling blade. In this class of rufflers as recently generally 20 constructed a regulating screw has been provided for regulating the stroke of the ruffling blade by taking up more or less lost motion, such regulating screw being mounted in a threaded ear or part. See, for example, 25 U. S. Patents Nos. 1,041,730, 1,044,645, and 1,261,628. In the present improved construction the regulating device consists of a plate having an opening of varying width and into which opening a projection on the 30 pendulous lever extends, said regulating plate being pivotally mounted so that it may be adjusted to different lateral positions to bring parts of the said opening of different widths into register with the said projection 35 on the pendulous lever, means being provided for retaining the said regulating plate in different positions of adjustment.

In the accompanying drawings Figure 1 40 is a side view of the improved ruffler, and Fig. 2 is a plan view thereof. Fig. 3 is a bottom view of the regulating plate, and Fig. 4 a detail view of the retaining pawl therefor.

Referring to the drawing, 12 denotes the 45 frame of the ruffler comprising a presser foot part 13 adapted to be attached to the presser bar of the sewing machine. Pivotally mounted on the upright side portion of the frame is a pendulous lever 14 the 50 lower end of which is jointed to a sliding part 15 carrying the ruffling blade 16 which co-operates with the usual separator plate 17 fixed to the frame part 12 of the ruffler. The operating lever 18 is pivotally mounted 55 on the frame part of the ruffler coincidentally

with the pendulous lever 14 and is forked at its forward end for engagement with a pin or roller stud on the needle bar of the machine. The parts thus far described are of the usual construction and operate in the usual 60 manner.

In the present improved construction the pendulous lever 14 is provided with an upwardly projecting part or short arm 19 which extends into an opening 20 formed in a 65 regulating plate 21, said regulating plate being pivotally attached, by means of a pin or screw 22, to a laterally extending lug or ear 23 formed on the operating lever 18. The opening 20 is tapered or, in other words, 70 is of varying widths at its different lateral parts between the side walls of said opening and which side walls contact with or engage opposite sides of the said arm 19 to operate the pendulous lever 14 with which 75 the ruffling blade 16 is connected. The pivotal mounting of the regulating plate enables the same to be adjusted to different lateral positions to bring different parts of the opening 20 into register with the short 80 arm or projection 19 on the pendulous lever 14 so that there will be more or less lost motion between the operating lever 18, having a constant movement, and the said pendulous lever from which latter the ruff- 85 fling blade is operated.

Attached to the ear 23 on the operating lever 18 is a spring pawl or retaining plate 24 having a tooth 25 adapted to engage an indented or roughened portion 21^a on the 90 under side of the regulating plate 21 in order to retain said plate in different positions of adjustment.

Owing to the fact that the regulating plate 21 and the parts co-operating therewith 95 may be stamped out of sheet metal the improved construction enables rufflers embodying the present improvement to be manufactured more cheaply than similar rufflers heretofore in use in which the means for 100 regulating the strokes of the ruffling blades required screws and tapped parts entered thereby.

Having thus described my invention I claim and desire to secure by Letters Patent: 105

1. In a sewing machine ruffler, the combination with an operating lever, of a pendulous lever having a short arm or projection, a ruffling blade operated from said pendulous lever, an adjustable regulating plate 110

mounted on said operating lever and having an opening entered by said arm or projection, said opening having varying widths at its different parts, and means for retaining said regulating plate in different positions of adjustment.

2. In a sewing machine ruffler, the combination with an operating lever provided with a laterally extending lug or ear, of a pendulous lever having a short arm or projection, a ruffling blade operated from said pendulous lever, an adjustable regulating plate pivotally mounted on said lug or ear and having an opening entered by said arm or projection, said opening having varying widths at its different parts, and means for retaining said regulating plate in different positions of adjustment.

3. In a sewing machine ruffler, the combination with an operating lever, of a pendu-

lous lever having a short arm or projection, a ruffling blade operated from said pendulous lever, an adjustable regulating plate mounted on said operating lever and having an opening entered by said arm or projection, said opening having varying widths at its different parts, and means for retaining said regulating plate in different positions of adjustment, said retaining means comprising an indented or roughened portion 25 on said regulating plate and a spring-pressed member engaging said indented or roughened portion.

In testimony whereof I affix my signature in the presence of two witnesses.

HERBERT H. RUSSELL.
